CONCRETE REINFORCEMENT

Charles Weichold, Cincinnati, Ohio

Application July 6, 1931, Serial No. 543,975

8 Claims. (Cl. 72—61)

It is the object of my invention to provide a concrete reenforcement in which the reenforcing element is of cross-sectional hollow form whereby lightness and increased superficial area relative to weight of the reenforcing element is obtained; further, to provide a hollow reenforcing element extending lengthwise in the concrete; further, to provide the wall of the hollow reenforcing element with holes through which the concrete poured thereabout passes into the hollow of the reenforcing element for connecting the concrete at the outside and at the inside of said reenforcing element; and, further, to provide crossing keys in said holes which are imbedded in the concrete and serve as anchoring members.

It is the object of my invention, further, to provide cross-sectionally bowed reenforcing elements, the hollows of which are presented toward each other, and which have their margins connected for forming hollow reenforcing elements; further, to provide tubular supplemental reenforcing elements in said hollow structures; further, to provide concrete filling in the hollows of said tubes and said hollow structures; and, further, to provide a novel slip connection between the butt ends of reenforcing elements comprising oppositely bowed reenforcing strips, the margins of which are connected.

It is the object of my invention, further, to provide novel portable reenforcing concrete beams; and, further, to provide novel portable reinforced concrete beams including reenforcing elements having tying connections between them.

The invention will be further readily understood from the following description and claims, and from the drawings, in which latter:

Fig. 1 is a side elevation of one of my improved reenforcing structures, partly broken away.

Fig. 2 is a cross-section of the same, taken on the line 2—2 of Fig. 1.

Fig. 3 is a side elevation of my improved reenforcing structure containing a reenforcing tube, partly broken away.

Fig. 4 is a cross-section of the same, taken on the line 4—4 of Fig. 3.

Fig. 5 is a side elevation of a reinforced concrete beam containing my improved reenforcing structure, partly broken away.

Fig. 6 is a cross-section of the same, taken on the line 6—6 of Fig. 5, and containing the inner reenforcing tube and a cross key member.

Fig. 7 is a perspective view of a pair of my reenforcing structures containing an internal

tube and arranged end to end, and a slip joint member connecting said ends, and partly broken away.

Fig. 8 is a side elevation of a portable reenforced concrete beam containing my improved reenforcing members, partly broken away.

Fig. 9 is a cross-section of the same, taken on the line 9—9 of Fig. 8.

Fig. 10 is a side elevational view of a detail of the same, partly broken away.

Fig. 11 is a side elevation of another form of my improved portable reinforced concrete beam shown in the form of a post, and partly broken away; and,

Fig. 12 is a cross-section of the same, taken on the line 12—12 of Fig. 11.

My improved reenforcement structure comprises a strip which is cross-sectionally formed with a median outwardly bowed portion 21, the curve of which merges into inwardly bowed portions 22 at the respective sides of the median outwardly bowed portion, the outer margins of said inwardly bowed portions forming flanges 23 at the respective sides of the formed strip. The cross-sectional curvature of the structure is in the form of an ogee curve at each side of the longitudinal middle of the strip, the ogee curves merging with each other along the middle of the strip and flaring outwardly as flanges at both sides of the strip.

There are preferably two of such strips 24, 25, the hollows of which are presented toward each other and the flanges of which are connected for forming a cavity 26 extending lengthwise of the structure.

The flanges at each side of the strips preferably comprise a flange, the outer edge of which is provided with a reverse bend 27 for forming an inwardly extending lip 28 whereby a groove 29 is formed extending lengthwise along the inside of the side margin of the strip, in which the side edge 30 of the other of the strips is received and clamped for forming a rigid structure. Such a seamed margin preferably extends lengthwise of the connected strips at each side of the same.

The side walls of the structure are provided with holes 35. These holes are shown in the side walls of each of the strips. They are preferably arranged in pairs comparatively close together lengthwise of the strip, as shown by the pairs of holes bracketed by the bracket 36 in Fig. 1. Such pairs of holes are preferably repeated at longer intervals throughout the length of the strip, as exemplified in Fig. 1.

For further reinforcement of the reenforcing

strip, a tube 37 extends lengthwise throughout the hollow between the connected bowed strips, extending into the bows of said strips and between the bases of the ogee curves thereof, for instance as exemplified in Fig. 4.

The inwardly curved portions of the ogee curvatures of the strips preferably contact the tube at various points around the circumference of the latter. The tube and the curved strips 10 strengthen each other and afford mutual support for avoiding bending or distorting of the reenforcing structures. The tube is preferably clamped between the walls of the strips. The tube may be inserted lengthwise into the cavity 15 between the mating strips, or the mating strips may be connected thereabout.

The holes 35 in the sides of the strips preferably extend into the crown portions of the strips beyond the circumference of the inner tube.

20 Cross keys 38 may be received through selective ones of the mating holes and extend outwardly beyond the respective sides of said reenforcing structure and form reenforcing positioning or anchoring pieces in the concrete.

25 The concrete is represented at 39. It may be of suitable composition and be poured while wet or plastic in a suitable form. The concrete is arranged to flow through the holes 35 and fill the cavity 26 in the interior of the bowed strips, 30 or, if combined with a tube 37, to fill the cavities 41, 42, between said tube and said strips. If desired, the tube may be provided with holes 43, 44, spaced apart in the length thereof, through which plastic concrete or composition may pass 35 into the interior of the tube and into the cavities 42.

If desired, the holes 35 and the tube may be omitted, and, if further desired, the interiors of said tube and of the cavities 26, 41, 42, may be 40 filled with concrete independent of the pouring of the concrete about the reenforcing structure.

For the purpose of connecting such reenforcing structures end to end similarly formed connecting strips 46, 47, may be provided, comprising 45 outwardly crowned formations 51, inwardly curved formations 52, merging therewith, the bases of the latter forming flanges 53, and the curvatures being such that the strips are respectively of ogee curvature at each side of their 50 median lines.

These strips have their hollowed portions presented toward each other about the respective ends of the abutting reenforcing structures, forming telescoping connection therewith. One 55 of the flanges at each side of the connecting joint is provided with a reverse bend 57 terminating in a flange 58 for forming a groove 59 in which the side edge 60 of the other flange of the other bowed joint strip and the clamped edges 61 at 60 one side of the respective abutting ends of the reenforcing structures are received, the other side of said abutting ends being similarly connected.

The reenforcing structures are employed either 65 singly as exemplified in Figs. 5 and 6, or a number of the same are employed, as exemplified respectively in Figs. 8, 9 and 10, and in Figs. 11 and 12, for forming portable reenforced concrete beams.

70 Referring to Figs. 8, 9 and 10, eight of such reenforcing structures 62 are spaced apart and connected by connections 63 which are heavy wires looped about reenforcing structures by means of loops 64, upright stretches 65 extending 75 between upright rows of the reenforcing

structures and a cross stretch 66 extending between the rows of connected reenforcing structures at the bottoms of said rows. At the tops of the rows, the cross-key 138 extends through the holes of the top ones of the reenforcing structures, connecting said reenforcing structures and forming a cross stretch therebetween. The upper ends of the connections 63 are formed with eyes 68 received about the ends of the cross keys for suspending the connections and the reenforcing structures therein.

The concrete 67 is poured about such connected reenforcing structures while suitably supported in a form, the form into which the concrete is poured determining the outer shape of the portable reenforced concrete beam.

The form of the portable reenforced concrete beam shown in Figs. 11 and 12 is similar to the form of portable reenforced concrete beam shown in Figs. 8, 9 and 10, but employs a less number of reenforcing structures, four of these reenforcing structures being exemplified, the parts being designated by similar but primed reference numerals.

These portable reenforced concrete beams form 100 integral reenforced concrete building elements which may be used as stringers, posts, joists, cross beams and other elements of a building, and be connected by poured concrete, for erecting the framework of a building structure similar to the steel framework of steel skeleton buildings, and for producing a concrete skeleton of a building similar to present concrete skeletons of buildings without however the necessity of erecting the forms it is now necessary to construct on 105 the building site in which to pour the concrete for the building.

The portable reenforced concrete beams mentioned may be preformed at a suitable place where this can be economically accomplished, 110 and where the concrete may be suitably treated for enhancing its strength, and where the same forms can be used repeatedly for producing beams of desired sizes and strengths, and these preformed beams may then be transported to 115 the site of the building being erected and be hoisted or moved into place in manner similar to the present day handling of steel beams. They may also be used as railway ties.

My improved reenforcing structure provides 120 maximum strength with a minimum weight of re-enforcing. My improved reinforcements may be made out of sheet metal rolled or otherwise shaped into the proper form and punched or otherwise manipulated for providing the holes. 125 The cross-sectional curvatures and the presenting of oppositely bowed strips toward each other and the connecting of the respective margins thereof provide for maximum strength with minimum weight of the reenforcing. It also presents rounded edges of the metal reenforcing to the concrete, and avoids the presenting of sharp edges of metal at its sides to the concrete, sharp edges in such relation having been 130 found detrimental.

My improved device also provides means whereby the concrete is located on the exterior as well as in the interior of my improved reinforcements, and provides means whereby the reinforcements may be keyed lengthwise in the concrete.

Having thus fully described my invention, what I claim as new, and desire to secure by Letters Patent, is:

1. A concrete reenforcement comprising oppositely presented cross-sectionally bowed par- 150

- allel strips having connected margins and forming a hollow between said strips, a reenforcing tube in said hollow to form a space between said connected strips and said tube, and hardened fillings in said tube and in said space. 80
2. A concrete reenforcement comprising oppositely presented cross-sectionally bowed parallel strips each of which at each side thereof is formed with an ogee curvature the inner margins of which merge with each other to form a bowed crown for the strip and the spaced margins of which form laterally outwardly extending flanges, the flanges of the strips presented toward each other for forming a hollow between said strips, and one of the flanges at each side of the structure provided with a reverse bend and an inwardly extending lip forming an inner groove in which the other flange is received. 85
3. A concrete reenforcement comprising oppositely presented cross-sectionally bowed parallel strips each of which at each side thereof is formed with an ogee curvature the inner margins of which merge with each other to form a bowed crown for the strip and the spaced margins of which form laterally outwardly extending flanges, the flanges of the respective strips presented toward each other for forming a hollow between said strips, one of the flanges at each side of the structure provided with a reverse bend and an inwardly extending lip to form an inner groove in which the other flange is received, and a tube in said hollow between said strips. 90
4. A concrete reenforcement comprising oppositely cross-sectionally bowed parallel strips, each of which at each side thereof is formed with an ogee curvature the inner margins of which merge with each other to form a bowed crown for the strip and the spaced margins of which form laterally outwardly extending flanges which are connected together to form a connected structure, the flanges of the strips presented toward each other for forming a hollow between said strips, and said connected structure provided with holes forming passageways for plastic concrete between the outside and the inside of said connected structure. 100
5. A concrete reenforcement comprising oppositely cross-sectionally bowed parallel strips, each of which at each side thereof is formed with an ogee curvature the inner margins of which merge with each other to form a bowed crown for the strip and the spaced margins of which form laterally outwardly extending flanges which are connected together to form a connected structure, the flanges of the strips presented toward each other for forming a hollow between said strips, and said connected structure provided with holes forming passageways for plastic concrete between the outside and the inside of said connected structure. 110
6. A concrete reenforcement comprising oppositely cross-sectionally bowed parallel strips, each of which at each side thereof is formed with an ogee curvature the inner margins of which merge with each other to form a bowed crown for the strip and the spaced margins of which form laterally outwardly extending flanges which are connected together to form a connected structure, the flanges of the strips presented toward each other for forming a hollow between said strips, a reenforcing tube in the hollow of said structure, said connected structure and said tube provided with holes forming passageways for plastic concrete between the outside of said connected structure and the insides of said connected structure and of said tube. 120
7. A concrete reenforcement comprising oppositely cross-sectionally bowed parallel strips, each of which at each side thereof is formed with an ogee curvature the inner margins of which merge with each other to form a bowed crown for the strip and the spaced margins of which form laterally outwardly extending flanges which are connected together to form a connected structure, the flanges of the strips presented toward each other for forming a hollow between said strips, a reenforcing tube in the hollow of said structure, said connected structure and said tube provided with holes forming passageways for plastic concrete between the outside of said connected structure and the insides of said connected structure and of said tube, and keys in selective ones of said holes in said connected structure extending outwardly beyond said connected structure. 130
8. A concrete reenforcement comprising oppositely presented telescoping cross-sectionally bowed reenforcement strips and joint strips, each of said strips at each side thereof formed with an ogee curvature the inner margins of which merge with each other to form a bowed crown for the strip and the spaced margins of which form laterally outwardly extending flanges, the flanges of said reenforcement strips and of said joint strips respectively presented toward each other with said joint strips outside said reenforcement strips for forming a hollow structure, one of the flanges of said reenforcement strips and of said joint strips at each side of the structure provided with a reverse bend and an inwardly extending lip forming an inner groove, the other flanges of said reenforcement strips received in said grooves in said reenforcement strips to form flanged edges, and said flanged edges and the other flanges of said joint strips received in said inner grooves of said joint strips. 140

CHARLES WEICHOLD.
